UNITED STATES PATENT OFFICE.

CHRISTOPHER H. OLSON, OF DECATUR, ILLINOIS.

SCREW-DRIVER.

SPECIFICATION forming part of Letters Patent No. 278,261, dated May 22, 1883.

Application filed December 2, 1881. Renewed September 28, 1882. (No model.)

To all whom it may concern:

Be it known that I, CHRISTOPHER H. OLSON, a citizen of the United States, residing at Decatur, in the county of Macon and State of Illinois, have invented a certain new and useful Screw-Driver, of which the following is a specification, and which has never been patented to me nor to others, with my knowledge and consent, in any foreign country.

10 The invention will be understood as set forth in the following specification and claims.

In the drawings accompanying and forming a part of this specification, Figure 1 shows my device entire. Fig. 2 is a section, and Fig. 3 an enlarged representation, of the handle and collar. Fig. 4 shows the pawl attached to the end of the handle.

15 A is the shaft that carries the screw-driver. This shaft is provided with a screw-thread or worm, extending nearly or quite over its entire length. B is the handle, constructed to receive and hold the projection of band b.

C is the collar, grooved in its inner surface, to conform to the projection on the shaft, and 20 also grooved in its outer circumference to receive band b. The collar C is formed in halves, as shown in Figs. 2 and 3, and placed together around the shaft A, and the band b consists of a piece of small metallic rod bent around the 25 collar and the ends extended to form the means for attaching the handle.

30 f is a ratchet formed on the exterior of the

collar C, and e is a spring-pawl attached to handle B, as shown in Fig. 4. The pawl e is let into a notch or cut-out portion of the handle, and is preferably formed of two spring-legs—one to engage the ratchet and the other to rest upon the offset in the handle and insure the engagement of the other limb with the ratchet. In operation, the screw-driver is 35 placed in position and the handle forced down, thereby revolving the shaft and driving the screw. Should one stroke of the handle be insufficient, the operation may be repeated, as the collar will revolve in the band on the upstroke 40 without affecting the shaft.

Having thus described my invention, I claim as new and desire to secure by Letters Patent—

1. In a screw-driver, the combination of the threaded shaft A, threaded split collar C, provided with the ratchet f, with the encircling band b, handle B, and pawl e, substantially as set forth.

2. In a screw-driver, the combination of the threaded shaft A, threaded collar C, provided with the exterior ratchet, f, and divided band b, encircling said collar and projecting at the ends to form the means of attachment for the handle, with said handle B and spring-pawl e, all substantially as herein set forth.

CHRISTOPHER H. OLSON.
